UNITED STATES PATENT OFFICE

EMANUEL J. PERRY, OF NEW BEDFORD, MASSACHUSETTS, ASSIGNOR, BY MESNE ASSIGNMENTS, TO THE AMERICAN LAUNDRY MACHINERY COMPANY, OF NORWOOD, OHIO, A CORPORATION OF OHIO

WASHING MACHINE

Application filed August 13, 1925. Serial No. 50,075.

The invention relates to improvements in washing machines adapted for use in laundries and the like.

The invention more specifically appertains to washing machines of the unloading type such as broadly described in my Patent, No. 1,400,977. The apparatus can be also used as a dyeing machine.

It is an object of the present invention to 10 provide improved mechanism for rotating the washing cylinder of a washing machine and for elevating or moving said cylinder to a position to one side of the casing thereof to permit the discharge of garments from the 15 cylinder and to return the cylinder to the casing after such operation.

The invention further comprises improved 20 means for controlling the rotation of the cylinder at the time it leaves the casing so that said cylinder can be stopped and will remain in a stationary position at a point where the garments can be most conveniently discharged therefrom.

The invention further comprises improved 25 controlling means for driving pulleys for rotating the cylinder and for the pulleys for raising and lowering the cylinder from the casing.

In the accompanying drawings. 30 Fig. 1 is an end elevation of the washing machine with the casing in its closed or washing position.

Fig. 2 is a view, similar to Fig. 1, with the 35 casing in its open position and the washing cylinder partially swung therefrom.

Fig. 3 is a view of the opposite end of the 40 device with the parts in the same position as in Fig. 1.

Fig. 4 is a transverse sectional view showing the manner of driving or rotating the 45 washing cylinder.

Fig. 5 is an end view, similar to Fig. 3, with the casing in its open position and the 50 washing cylinder swung to its unloading position.

Fig. 6 is a front elevation of the device with the parts in the position shown in Fig. 5.

Fig. 7 is a rear elevation of the device. 55 Fig. 8 is an enlarged longitudinal sectional

view illustrating the mechanism for rotating and swinging the washing cylinder.

Fig. 9 is a top plan view of what is shown in Fig. 8.

Fig. 10 is a sectional view on the line 55 10-10 of Fig. 8.

Fig. 11 is a similar view on the line 11-11 of Fig. 8.

Fig. 12 is an enlarged transverse sectional view of the brake mechanism of the washing 60 cylinder, and

Fig. 13 is a longitudinal sectional view on the line 13-13 of Fig. 12.

Referring now more specifically to the drawings, wherein like reference characters 65 indicate corresponding parts, the numeral 1 designates the casing of the washing machine which may be constructed of any approved material.

This casing is provided with supporting 70 legs 2 constituting a rest therefor and is likewise provided with a water supply pipe 3 and a drain pipe 4 as disclosed in Fig. 1. The casing is constructed of imperforate material so as to prevent the discharge of water therefrom and has a swinging closure or door 5 at its front portion provided with an opening handle 6, the door or closure being permanently connected with side wall portions 5' of the container so that when it is 80 open the inner rotating cylinder to be hereinafter described can be moved from the casing. The swinging door or closure 5 is pivotally attached along its rear side 5a to the casing so that when this door is swung 85 open it moves the segmental side portions 5' thereof along with it, which segmental portions carry portions fitting into recesses in the bearing housing for the rotating cylinder as will be more fully hereinafter described. 90 It will be apparent, by inspecting Fig. 5, that the sections 5' of the casing 1 mate with the stationary portions of the end walls of the casing to form circular ends. These sections 5' are joined at their peripheries by the cover 5 which is formed with guides 5d to receive the sliding cover section 5c. When the cover 5, with its end walls 5', is elevated to permit the cylinder 9 to be moved outwardly of the casing, the cover section 5c will slide auto-

100
95
100

- matically along the guides 5d for providing an opening of sufficient size to permit the cylinder 9 to be moved out of and into the casing 1.
- 5 It will be understood that the invention pertains to a washing machine of the unloading type. That is to say, the machine is provided with a washing cylinder 9 journaled in the casing 1 so as to freely rotate therein.
- 10 This cylinder has perforated walls to permit water to pass therethrough and is movable to a position as shown in Fig. 5, that is, beyond one side of the casing. The washing cylinder 9 carries at each side a spider 10 bolted to the end walls of the cylinder and receiving or provided with bearing trunnions 11 on which the cylinder turns. The spiders 10 furthermore carry peripheral gears 12 which are adapted to mesh with
- 15 driving gears to be hereinafter described by means of which the cylinder is rotated. The cylinder furthermore is provided with slideable doors 13 which are capable of being manually opened or closed for the purpose of inserting or removing garments to or from the cylinder. It will be appreciated that this washing cylinder normally rotates in the casing 1. The movement imparted to this cylinder is first a rotary movement in one direction and then a rotary movement in the opposite direction, the present invention comprehending improved means for alternating the direction of rotation of the cylinder. Such rotation causes a thorough cleansing or washing of the garments in the cylinder. When said garments are so washed the cylinder is then shifted to the position shown in Fig. 5 or moved out of the casing 1. When in such a position it is obvious that a mere opening
- 20 of the doors 13 of the cylinder causes the contents thereof to drop by gravity from the cylinder. The improved mechanism for rotating the cylinder will now be described.
- 25 *Rotating mechanism for washing cylinder*
- 30 The washing cylinder as hereinbefore described is provided with peripheral gears 12 at each side thereof carried by the spiders 10. Secured to the end walls of the washing cylinder, see Fig. 5, are brackets or supports 14 receiving a rotating shaft 15. This shaft is journaled in suitable bearings formed in these brackets. Mounted on the shaft near one end thereof are the pulleys 16, 17, and 18,
- 35 the pulleys 16 and 17 being idler pulleys, while the relatively narrow pulley 18 constitutes a driving pulley keyed to the shaft 15. A pair of driving belts 19 and 20 are employed for rotating the fixed pulley 18.
- 40 The belt 20 is a crossed belt while the belt 19 is not crossed, it being apparent that the said belts will serve to rotate the fixed pulley 18 in opposite directions when placed thereon. It is, of course, manifest that when either belt
- 45 is on the fixed pulley 18 rotation is imparted to the shaft 15. When, however, the belts are on the pulleys 16 and 17 this shaft will not be rotated. The end of the shaft 15 carries a sprocket 21 around which a driving chain 22 passes, the said chain traveling around a sprocket 23 mounted on a transverse shaft 24 in the rear of the machine, which shaft is journaled in suitable bearings 25 and extends entirely across the machine. The shaft 25 has keyed thereto, the gears 26 which enter the casing 1 of the machine, and are so positioned as to mesh with the peripheral gears 12 on the spiders of the washing cylinder when said cylinder is in the casing 1. The rotation of this shaft will therefore cause the cylinder to be rotated in the casing.
- 50 In washing machines of this type it is desirable to alternate the direction of rotation of the washing cylinder. It is for this purpose that the two belts 19 and 20 are employed. It is also desirable that this alternating rotation be accomplished automatically, and this invention embodies improved mechanism for controlling the direction of rotation of the cylinder when the device is in operation. Assuming, therefore, that the cylinder is in the casing 1 and the belts 19 and 20 are on the idler pulleys 16 and 17, if it is desired that the cylinder be then rotated the hand lever 26' is engaged, which lever is shown at one side of the machine, and moved forwardly over the ratchet 27. Its end is ball shaped as indicated by the character 28, and at its lower end engages or seats in a yoke 29 on a lever 30 when the cylinder is lowered. The lever is connected by a link 31 with a bell crank arm 32 which is in turn connected by a link 33 connected to a controlling cam 34 disposed above the machine and adjacent the driving and reversing mechanism. The reversing mechanism embodies a housing 35 mounted on a suitable support extending from the casing and having a vertical and a horizontal portion. This support is provided with separated bearings 36 slidably receiving a shifter rod 37 carrying near one end suitable belt shifters 38 and 39 through which the driving belts 19 and 20 pass. These shifters are fixedly attached to the shifter rod 37 so that a movement of said rod will impart a corresponding movement to the belt shifters. The rod has mounted thereon and keyed thereto a weighted cam 40 disposed within a housing 41 which limits the extent of movement of the cam endwise in either direction. This weighted cam 40 has a tongue portion 42 which is formed with a slot 43 to couple the reversing mechanism which will be hereinafter described. In reverting now to the operation of the controlling cam 34, it will be found that the shifter rod 37 at its outer end is provided with a pin 44 and the weight of the cam 40 normally serves to throw this pin downwardly. By moving the lever 26' to the right in Fig. 1

the controlling cam 34 is shifted so that it is moved away from contact with the pin 44. The weight of the cam 40 on the shifter rod 37 therefore causes this cam to drop and rotate with it the loosely mounted rod 37. When this cam drops it becomes engaged with the automatic shifting mechanism to be now described, causing the rotation of the container in alternate directions.

10 Mounted upon the shaft 15, adjacent the loose pulley 16, there is a worm gear 45 which worm is loose on this shaft. The worm carries interlocking lugs 46 engageable with corresponding lugs on the hub of the loose pulley 16. The driving belt 20 is substantially wider than the belt 19 and is so arranged that even if this belt is thrown on the driving pulley 18, it slightly extends beyond this pulley and onto the adjacent pulley so that this pulley is always rotating irrespective of which belt is engaged with the fast pulley 18. This rotation therefore rotates the worm 45. This worm meshes with a circular gear 46' journalled in suitable bearings and disposed above the shaft 15. Pivotaly mounted on a bracket 47 is a reversing arm 48, the said arm having an open interior 49, the inner surface of which interior coacts with a shifting pin 50 eccentrically mounted on the gear 46'. The connection is such that as the gear 46' rotates it will rock the arm 48 back and forth, and it is this movement that is imparted to the shifter rod 37 for the purpose of alternately throwing the straight and crossed belts in driving relation with the fixed pulley 18.

15 It will be recalled that the weighted cam 40 at its lower end is provided with a slot 43. The shifter arm 48 is, at its upper end, formed with an offset pin 51 which enters into the said slot 43 when the controlling cam 34 has been shifted so as to become disengaged from the finger or pin 44 in allowing the weighted cam 40 to drop. The moment 20 the cam which is fixed to the shifter rod 37 so drops, it operatively associates itself with the shifter arm 48 and moves with this arm. Assuming that the arm is moved to the left when this engagement takes place, the continued movement thereof will cause a movement of the shifter rod 37 to the left so that the belt shifter 38 for the belt 19 will move this belt over onto the fixed pulley 18. Rotation will then be imparted to the shaft 24. 25 Through the chain 22 and gear 23. The driving gears 26 coaxing with the peripheral gears 12 on the spiders of the cylinder will rotate this cylinder in one direction. As soon as the pin 50 on the gear 46' has reached the limit of its outward movement, which pin, as will be noted, is eccentric, it, of course, then moves inwardly and engages an opposite surface 49 of the interior opening found in the shifter arm 48 and therefore soon moves 30 this rod to the right. After a predetermined

movement, the belt shifter 38 moves its belt 19 from the fixed pulley 18 onto the idler pulley 17. Immediately after this movement, the belt shifter 39, however, moves its belt 20 onto the fixed pulley 18 which causes 35 a reversal in the direction of rotation of the washing cylinder because of the fact that the belt 20 is crossed. The opening in the shifter rod 48 and the walls 49 of this opening are so curved as to permit a substantial 40 rotation of the washing cylinder in one direction before reversing its direction of rotation. This automatic operation continues until the clothes have been washed. When 45 this has occurred, and it is desirable to stop the rotation of the cylinder, the lever 26' is again grasped and moved toward the operator which, from the levers 30 and 32 and links 31 and 33, rotates the controlling cam 34 on its pivot until said cam rides under and 50 engages the pin or finger 44 and serves to rotate the shifter rod 37 because of the fact that this pin is keyed to said rod. When the rod is so rotated, the cam 40 thereon is also 55 lifted and this cam is raised until it is lifted from engagement with the pin 51 on the shifter arm 48. The cam 34 is so formed that as it is moved it shifts the rod 37 to a neutral position, at which time the belts 19 and 20 are on the idler pulleys 16 and 17, and as 60 before stated, it also lifts the cam 40 from the pin 51 so that the shifter rod is uncoupled from the shifter mechanism.

Braking assembly for washing cylinder

At the time the rotation of the cylinder is stopped, the movable door 5 for the casing is opened and the cylinder is to be then moved from the machine. Just before the rotation of the washing cylinder 9 ceases, it is desirable to brake or lock the cylinder so that when the cylinder is removed from the casing it will occupy a position as shown in Fig. 5 in which position the garments may readily fall therefrom. One of the bearing trunnions 11 of the cylinder is therefore provided with a braking drum 52. This drum is housed within a casing 53. Disposed around the drum is a brake band 54 of the type now commonly employed in motor vehicles being pivotally supported at the point 55 while the opposite end of the band has an open connector 56 receiving a shiftable cam 57. When this cam 57 is operated, naturally the brake is drawn around the drum 52 and stops the rotation of the shaft 11 which in turn controls the rotation of the washing cylinder. There is also mounted on the trunnion 11 a member 58 having a peripheral surface over which a crank arm for actuating the brake operating cam 57 rides. There is an elongated slot 58a in the member 58, so that same can be adjusted in either direction, so that the positioning of the cylinder can be regulated. It will be understood

that this brake operating cam 57 is mounted on a supporting shaft 59 disposed within the housing 53, one end of this shaft being connected with the lever 26', which has heretofore been described. The opposite end of the shaft 59, at a point near the cam 57, carries a locking dog 60 which is keyed to the said arm or shaft 59. A shiftable manually operated lever 61 extends through the housing 53 adjacent this cam 60, and said lever rides in a cam slot in this housing. The lever lies adjacent a lever 62 mounted on the rod 59 which has a dog face 63 adapted to coact with the dog 60 keyed to this shaft. 10 When this lever 61 is moved in the cam slot it shifts the dog face 63 into binding contact with the dog 60. The lever or rod 62 at its lower end carries an anti-friction wheel or bearing 64 which rides on the peripheral surface of the member 58. This member 58 is, as before stated, eccentrically mounted on the trunnion 11. When the hand lever 61 is shifted, as described, the rotation of the trunnion 11 will, through the member 58, impart 20 a rocking movement to the arm or lever 62 which will turn the cam 57 and draw the brake band 54 tightly around the brake drum 52. It will thus be seen that the locking of the rotating cylinder is more or less automatic, and by arranging the parts as herein described, this cylinder will always be locked, due to its own rotary movement, in a position where it will discharge its garments directly therefrom, or in other words the cylinder is 25 locked so that when it is ejected or moved from the casing, the door controlled opening will be facing the floor.

Mechanism for elevating and lowering the cylinder from the casing.

After the cylinder has been so locked the movable closure or door 5 of the casing is opened, so that the washing cylinder may be moved from the casing to eject the clothes therein. To move this cylinder from the casing, driving pulleys 70, 71, and 72 are provided, the pulleys 70 and 72 being loosely mounted, while the pulley 71 is keyed to or rigidly attached to a sleeve 73 carrying at its 40 outer end a bevel gear 74 which meshes with a beveled gear 75 attached to a shaft 76 journalled in suitable bearings formed in a housing for these gears. The shaft 76 at its opposite end carries a worm 77 which meshes 45 with a gear 78 on a transverse shaft 79. A pair of driving belts 80 and 81 are provided for rotating the fixed pulley 71 in opposite directions. The shaft 79 carries gears 82 at each end thereof, said gears meshing with 50 large gears 83 supported in suitable housings 84 connected with the casing of the machine, which gears in turn mesh with gear segments 85. It will be observed that the trunnions 11 of the washing cylinder are supported in 55 bearings 86 of the gear segments 85. In

other words, the washing cylinder is directly mounted on these gear segments. The arms of the gear segments are journalled on supporting shafts 87 attached to the side walls of the casing and on which shafts the segments turn. The segments are provided with gear teeth 88 which, as before stated, mesh with the gears 83. As rotation is imparted to the gears 83 in one direction, the gear segments are lifted, carrying with them the washing cylinder so that said cylinder is moved outside of the casing, having been locked prior to this movement so that the door openings therein are directed downwardly, when the cylinder is out of the casing, to facilitate the discharge of clothes therefrom. If desired, suitable connections can be made between the gear segments 85 and the movable door 5 of the casing to open this door at the time the cylinder is to be moved therefrom. One form of such connections is illustrated in Figures 1, 2, 3 and 5 of the drawings. These connections comprise a pin 200 secured to and projecting laterally from each end wall 5' of the hood or the cover 5 and a fork member 201 pivotally mounted on each gear sector 85. The fork members are so arranged that they engage the pins 200 when the sectors and the cover are in their normal positions. As the sectors are rotated the forks exert an upward pressure on the pins 200, thus causing the hood to move upwardly about its pivot. During the upward movement the forks move about their pivots and force the cover to a fully opened position whereupon the forks disengage from the pins while the sectors continue their upward movement. When the hoods reach their fully opened position, the pins 200 are received and held by the pivotally mounted spring pressed latches 202. The fork members are each provided with a laterally projecting lug 203 which on the downward movement of the sectors engage the latch members and release them from the pins, whereupon the forks re-engage the pins and carry the cover to its closed position as the sectors move downwardly to their normal position. Any suitable means may be provided for normally maintaining the pivoted fork 201 in the position shown in Figure 5 while permitting it to assume its other active positions as illustrated in Figures 1 and 2 due to its coacting with the pin 200 and relative movement of the gear sectors and the casing cover. To lift the cylinder from the casing in this manner, manual means is employed for controlling the belts 80 and 81. A lever 90 is pivotally mounted at one side of the machine. This lever connects with a link 91 pivoted to a crank 92 attached to a shaft 93 which carries a cam 94. This cam 94 rotates in a bracket 95, which bracket carries a shifter rod 96. The shifter rod has rigidly connected therewith a finger 97 which rides in the cam 94. The outer end of this

shifter arm carries a shifter element 98 on opposite sides of which I provide the belt guides 99 and 100. If the lever 90 is moved in one direction this movement is imparted to the cam 94 which shifts the shifter element 98 due to the movement of the rod 96 so as to move one of the belts into operative relation with the fixed pulley 71. We will assume that this movement raises the washing cylinder from the casing. A lug 90a fixed to the segment comes in contact with lever "90" when the cylinder is approaching the upper limit of its travel—stopping the upward movement of the cylinder at the desired point. After the clothes have been dumped, the lever 90 is then moved in an opposite direction, and through the mechanism herein described the other belt is brought into contact with the fixed pulley 71 so that a rotation of this pulley returns the washing cylinder to the casing, and the lug comes in contact with lever 90 and brings the belts into neutral when cylinder is seated in proper place, after which the door of the casing is closed, the cylinder being then ready for further rotation. A more complete understanding of the automatic operation of the cylinder elevating and lowering mechanism may be had by reference to Figs. 3 and 5 of the drawings. In this figure the cylinder is shown in its outermost position and the lever 90 in its neutral position to which it has been moved by engagement therewith of the lug 90a secured to the gear sector. The lever 90 may be moved from the position illustrated in Figure 3 to the dotted line position shown in Figure 5 for throwing the transmission mechanism into operation to raise the cylinder from the casing. During the upward movement of the gear sectors and the cylinder carried thereby, the lug 90a will come into engagement with a projection 90b on one side of the lever and move the same to its neutral position which corresponds to the neutral condition of the transmission mechanism. In order to return the cylinder to the casing, the lever 90 is moved in the opposite direction from that shown in dotted lines in Figure 5, whereupon the transmission becomes effective and the gear sectors and cylinder move inwardly with respect to the casing. During this inward movement, the lug 90a comes into contact with the lower depending end portion 90c of lever 90, thus again throwing this lever to its neutral position and rendering the transmission mechanism inoperative. It will be understood however, that before the cylinder can be rotated, the braking mechanism therefor must be released. The invention contemplates the provision of means by which this braking mechanism is automatically released when the rotating mechanism for rotating the cylinder is placed in operation. This mechanism has been briefly described, but will be again referred to.

It will be observed that the lever 26' is connected through the lever 30, link 31, lever 32, and link 33 with the cam 34. A forward movement of this lever shifts the cam 34 so that the weighted cam 40 can drop and become engaged with the pin 51 on the shifter arm 48. This lever 26', however, is connected by a link 102 with a lever 103 which lever is in turn operatively connected with the bearing rod or support 59 on which the cam 57 is mounted. Before the ball end 28 of this lever engages the yoke 29 of the lever 30 to cause rotation of the washing cylinder, the lever 61 previously having been moved to release the clutch structure 60—63 the element 59 has been shifted, due to the connecting links 102 and 103, so as to release the brake coacting with the brake drum 52. The lever 26' therefore serves a dual purpose, namely, it releases the braking mechanism for the washing cylinder and at the same time, on a continued movement, throws the operating mechanism for rotating the cylinder into operation.

It is believed that from the foregoing description the invention can be clearly comprehended and it will of course be understood that many changes in the construction and operation of parts can be resorted to without departing from this invention.

Having thus described my invention, what I claim is:

1. In a washing machine, the combination with a casing, of a rotating washing cylinder therefor, means for rotating said cylinder, a brake mechanism, including a member rotatable with the cylinder and a non-rotatable retarding member, and means actuated by the movement of the cylinder for operating said mechanism to stop said cylinder in a predetermined position, said actuating means including a lever for the non-rotatable member and an element rotatable with the cylinder and engageable with the lever, when the cylinder occupies a predetermined position, to move the lever for applying the retarding member.

2. In a washing machine, the combination with a casing, of a rotating cylinder therein, means for rotating the cylinder, automatically operated means for braking said cylinder when it reaches a predetermined position, said means comprising a friction brake device coacting with the cylinder and including an operating arm, and an applying device consisting of an eccentric engaging said arm and operated by the movement of said cylinder to apply said braking device.

3. In a washing machine, the combination with a casing, of a rotating washing cylinder therein and movable into and out of the casing, means for rotating said cylinder alternately in different directions, a manually operable control for said rotating means, brake mechanism for the cylinder, means actuated by the movement of the cylinder

for applying said mechanism when the door of the cylinder is in a position to permit the discharge of clothes by gravity from the cylinder when the latter is disposed without the casing, and a control device for the brake actuating means connected to and operable by the said manual control for releasing the brake when the cylinder is started.

4. In a washing machine, the combination with a casing, of a cylinder therein, means for rotating the cylinder, a movable door for said cylinder, braking means for stopping said cylinder when the door reaches a predetermined position, a manual control for said braking means, a mechanism operable by the rotation of the cylinder for operating said braking means to stop said cylinder upon the shifting of said manual control to a braking position.

5. In a washing machine, the combination with a casing, of a cylinder therein, means for rotating the cylinder, a movable door for said cylinder, braking means for stopping said cylinder when the door reaches a predetermined position, a manual control for said braking means, a mechanism operable by the rotation of the cylinder for operating said braking means to stop said cylinder upon the shifting of said manual control to a braking position, said means comprising a braking drum, a braking band therefor, a cam for operating said band, an arm, an interlocking connection between said arm and said cam, and an eccentric carried by said cylinder for operating said arm.

6. In a washing machine, the combination with a casing, a cylinder rotatively disposed within said casing, a shaft to which said cylinder is secured, a brake drum on said shaft, a brake member adapted to engage said drum, a crank arm for actuating said brake member and adjustable eccentric means operatively connected with said cylinder and having operative engagement with said crank arm for actuating the latter.

7. In a washing machine, the combination with a casing, of a cylinder in said casing, means for moving said cylinder out of and into said casing, a movable cover for said casing, means actuated by said cylinder moving means during outward movement of said cylinder for opening said cover, a latch for holding said cover in open position, and means carried by said cover moving means for releasing said latch on the inward movement of said cylinder for permitting said cover to be closed.

8. In a washing machine, the combination with a casing, of a cylinder in said casing, pivotally mounted members whereon said cylinder is journaled for moving said cylinder into and out of said casing, a cover for said casing, a pin carried by an end wall of said cover, a pivotally mounted fork element carried by one of said pivotally mounted

members and engageable with said pin whereby to open said cover during outward movement of said cylinder, a latch element positioned to receive said pin and hold said cover in open position, and means operative upon the inward movement of said cylinder for releasing said latch member.

9. In a washing machine, the combination with a casing, a cylinder rotatably disposed within the casing, a brake mechanism including a member rotating with the cylinder and a non-rotatable member adapted for coaction with said first member, a normally inoperative brake actuating connection between the cylinder and said non-rotatable member, said connection including an element rotating with the cylinder, and means for rendering said connection operative whereby said non-rotatable member will be moved into engagement with said first member to stop the cylinder.

10. In a washing machine, the combination with a cylinder, of a casing for said cylinder, power means including a rockable segment on which the cylinder is supported for lifting the cylinder from the casing, a control lever for said power means, and means on said segment for automatically shifting the control lever to move the same to a neutral position when the cylinder reaches the limit of its upper or lower movements.

In testimony whereof I affix my signature.
EMANUEL J. PERRY.
